STICK FOR A MOLDED CONFECTION

Richard L. Wagner, Georgetown, Conn., assignor to
Diamond National Corporation, New York, N.Y., a
corporation of Delaware

Filed Nov. 15, 1963, Ser. No. 77,439

Term of patent 14 years

(Cl. D82—2)

FIG. 1.

FIG. 7.

FIG. 2.

FIG. 3.

FIG. 4.

FIG. 5.

FIG. 6.

FIG. 1 is a view in perspective of a stick for a molded confection showing my new design;

FIG. 2 is a plan view thereof;

FIG. 3 is a front elevational view thereof;

FIG. 4 is a section taken along the line 4—4 of FIG. 2, looking in the direction of the arrows;

FIG. 5 is an end elevational view of said stick for a molded confection;

FIG. 6 is a section taken along the line 6—6 of FIG. 2, looking in the direction of the arrows; and

FIG. 7 is a fragmentary plan view of one of the ends of the stick.

The handle or both stick ends are characterized each by a true semi-circular depression coupled with spaced longitudinal bars of true rectangular section extending from intermediate the ends of the raised rectangular chord which subtends the semi-circular depression which is an actual diameter, it being twice the radius of curva-

ture of the depressed semi-circle and the longitudinal bars are continuous between both stick ends all as shown.

I claim:

The ornamental design for a stick for a molded confection, as shown and described.
